AUTOMATIC FEED LINE CUTOFF AND DRAIN
FOR OIL BURNERSDonald E. Pressey, Stillwater, and Joseph M.
Conley, Orono, Maine

Application June 20, 1950, Serial No. 169,154

9 Claims. (Cl. 158—42.3)

1

This invention relates to an improved oil burner feed system and more particularly to a novel automatic feed line cut-off and drain especially suitable for use in conjunction with range burners and the like.

As is well known, the safe operation of a type of range burner prevalently in use requires that the oil level in the burner bowl shall not exceed a certain height, while flooding of the bowl involves a definite fire hazard.

It is therefore an object of the present invention to provide a safety device wherein, if for any reason the burner bowl should become flooded with oil, the supply of oil to the burner will be automatically cut off.

Another object of the invention is to provide a device wherein as excess oil becomes present in the burner bowl, such excess oil will be drained therefrom into the safety device, and wherein, after the oil in the safety device reaches a given level, said device will be automatically actuated to shut off the supply of oil to the burner.

And the invention seeks, as a still further object, to provide a safety device wherein, after the supply of oil to the burner has been shut off, the oil feed line extending between the device and the burner as well as the burner bowl will be drained of the oil therein.

Other and incidental objects of the invention will appear during the course of the following description thereof, and in the drawings:

Figure 1 is a diagrammatic sectional view showing our improved safety device installed.

Figure 2 is a vertical section showing the device set.

Figure 3 is a vertical section showing the device tripped.

Figure 4 is a horizontal section on the line 4—4 of Figure 2.

Figure 5 is an enlarged detail section showing the plunger set.

Figure 6 is an enlarged detail section showing the plunger set.

Figure 7 is a detail perspective view particularly showing the float lever and trigger bracket.

Referring now more particularly to Figure 1 of the drawings, we have shown a conventional range at 8. Mounted therein is a stand 9 which carries burners 10 each including a bowl 11. The structural details of the burners are not especially important. A conventional fuel tank is shown at 12, said tank being arranged near the range 8, and mounted at a point between the tank and range is a valve unit 13 including a metering valve 14 for each of the burners 10. The unit 13 is conventionally shown.

2

As seen in Figures 2, 3, and 4 of the drawings, our improved safety device includes an oblong casing 15 at one end of which is a float chamber 16, while at the other end of the casing is a plunger chamber 17, and closing the casing is a removable cover 18 which, between said chambers, carries an inspection plate 19. The plate 19 is freely removable to permit access to the casing.

At one side thereof, the float chamber 16 is provided with a nipple 20, and removably secured to said chamber at the upper end thereof is a cap 21 which carries a shut-off valve fitting 22. Clamped between the cap 21 and the float chamber is a pliable diaphragm 23 which closes communication between said chamber and the cap, and fixed to said diaphragm is a shut-off valve 24 which extends through the cap 21 into the fitting 22 to coact with the valve seat of said fitting. Fixed to the lower end of the stem of the valve is a collar 25, and it is now to be noted that the float chamber 16 is provided at the lower end thereof with a drain plug 26.

Extending into the plunger chamber 17 at its upper end, as particularly seen in Figure 5 of the drawings, is a plunger barrel 27 which is fixed to the cover 18, and freely slidable through the upper end wall of said barrel is a plunger 28. At its upper end, the plunger is equipped with a nut 29 which provides a knob for the plunger, and formed on the plunger is a head 30 terminating in a shoulder 31. Extending downwardly from the head is a tapered prong 32 having a piercing tip 33, and surrounding the upper end portion of the plunger within the barrel 27 is a spring 34 pressing downwardly upon the plunger. Formed in the lower end of the barrel at one side thereof is a vertical slot 35, and fixed to the head 30 of the plunger is a pin 36 extending freely through said slot.

Fixed to the lower end of the barrel 27 at a right angle to the slot 35, as more particularly seen in Figure 7 of the drawings, is a sheet metal bracket 37 having an upper pair of ears 38 and a lower pair of ears 39. Pivoted between the upper pair of ears 38, as particularly seen in Figure 6 of the drawings, is a trigger 40, the upper end of which is adapted to engage beneath the shoulder 31 of the head 30 of the plunger 28 for holding the plunger retracted in set position, and pressing the trigger to coact with the plunger is a bowed spring 41 disposed behind the lower end portion of the trigger.

Fixed to one side wall of the casing 15, as particularly seen in Figure 4 of the drawings, is a post 42, and pivoted upon said post is a valve lever 43. At one end, the lever 43 is provided

with a fork 44 which freely straddles the collar 25 of the valve 24 to coat therewith, and formed on the lever at its opposite end is a yoke 45 having an arcuate slot 45' which freely receives the pin 36 of the plunger 28. Thus, as seen in Figure 3 of the drawings, when the trigger 40 is released and the plunger 28 is shifted downwardly by the spring 34, the lever 43 will be rocked to move the valve 24 upwardly to closed position in engagement with its seat. However, as the travel of the plunger is greater than the travel of the valve, the slot 45' is provided in the yoke 45 of the lever 43 to permit the pin 36 to move down with the plunger the length of the slot before actuating the lever to close the valve 24. Furthermore, it is to be noted that at any time after the trigger 40 is tripped and the valve 24 is closed, the mechanism may be reset simply by grasping the nut 29 and pulling the plunger 28 upwardly until the trigger snaps under the shoulder 31. The lever 43 will, of course, be coincidentally rocked to return the valve 24 to open position.

Fixed to the bottom wall of the casing 15 at the lower end of the chamber 17, as particularly seen in Figure 5 of the drawings, is a nipple 46, the lower end portion of which provides a chamber 47, and formed on the nipple at the upper end of said chamber is an internal annular shoulder 48. Screwed into the nipple is a follower 49, and clamped between the follower and the shoulder 48 is a frangible disk 50 normally closing the chamber 47 with respect to the chamber 17. As brought out in Figure 3, the tip 33 of the plunger 28 will, when the trigger 40 is tripped and the plunger is snapped downwardly by the spring 34, puncture the disk 50 to establish communication between the chambers 47 and 17. Normally closing the nipple 46 at its lower end is a plug 51 which may be manually removed to expose the follower 49, after which the follower may be removed to free the disk 50 so that, after the disk has been ruptured, a new disk may be readily substituted in lieu thereof. Fixed to the nipple 46 at one side thereof is a pipe connection 52 communicating with the chamber 47 of the nipple.

Pivoted between the pair of ears 39 of the bracket 37 is a float lever 53 extending at one end into the chamber 16, and freely received in said chamber is a float 54 which is provided at its upper side with a loop 55 accommodating the lever therethrough for connecting the float with said lever. At its opposite end, the lever 53 is provided with a cam-head 56 disposed to coat with the lower end portion of the trigger 40. As will be perceived, rise of the float in the chamber 16 will rock the head 56 downwardly to press the trigger out of engagement with the shoulder 31 of the plunger 28 and thus trip the trigger and free the plunger.

Referring now again to Figure 1 of the drawings, a pipe 57 connects the tank 12 with the valve fitting 22, and leading from said fitting to the valve unit 13 is a pipe 58, while pipes 59 connect the metering valves 14 with the burner bowls 11. Thus, oil will normally flow by gravity from the tank 12 through the pipes 57 and 58 to the valve unit 13, and thence, under control of the valves 14, through the pipes 59 to the burner bowls 11.

Leading from the burner bowls 11 are overflow pipes 60, and connecting the pipes 60 with the nipple 20 of the float chamber 16 is a pipe 61, the pipes 60 and 61 being adapted to drain excess oil in the burner bowls into the float chamber. The exact manner of connection of the pipes 60

with the burner bowls 11 is not important. Connecting the pipe 58 with the pipe connection 52 of the nipple 46 is a branch pipe 62.

Normally, the plunger 28 will be set, as shown in Figure 2 of the drawings, so that the valve 24 will be held open to permit, under control of the valves 14, a free flow of oil from the tank 12 to the burner bowls 11, as previously described. However, if for any reason the burner bowls should become flooded with oil, excess oil in said bowls will be immediately drained off through the pipes 60 and 61 to the float chamber 16. The float 54 will thus be caused to rise, with the result that the lever 53 will be rocked to release the trigger 40 and trip the plunger 28. Consequently, the plunger will be snapped downwardly by the spring 34 to rupture the disk 50, while the lever 43 will be rocked to close the valve 24 and shut off the supply of oil to the burner bowls 11.

Since at the time the shut-off valve 24 is closed, the disk 50 is ruptured, oil remaining in the burner bowls 11 will drain back through the pipes 59, the valve unit 13, pipe 58, and pipe 62 into the chamber 47 of the nipple 46 and thence into the casing 15. The capacity of the casing is sufficient to hold all of the excess oil remaining in the burner bowls, as well as the oil in the pipes 59, valve unit 13, and a portion of the pipe 58, so that not only will the burner bowls 11 be drained of excess oil, but also the oil feed line itself will be drained of oil back to the point of connection of the pipe 62 with the pipe 58. As will be observed, the pipes 58 and 59 are inclined downwardly away from the burner bowls.

To reset the device, the plug 26 is removed and the casing 15 drained of oil. The plunger 28 is then lifted until the trigger 40 snaps under the shoulder 31 of the plunger, thus opening the valve 24. The plug 51 and follower 49 are then removed and a new disk substituted for the disk 50, following which the plug 26, follower 49, and plug 51 are replaced.

Having thus described our invention, we claim:

1. In a feed system for an oil burner, an oil supply tank, a feed line arranged to conduct oil from the tank to the burner, a shut-off device including a shut-off valve interposed in the feed line, an overflow line extending between the burner and said device and arranged to drain excess oil from the burner into said device, valve-closing means carried by said device and operatively connected with said valve, said valve-closing means being adapted to be set and being operable when released to force said valve closed and having a portion disposed to be grasped for manually actuating said means when released to open and close said valve, and float operated means mounted in said device and operable by the rise of the level of oil therein for releasing said valve-closing means, said closing means when released being movable to close said valve without disturbing the position of said float operated means and said float operated means being adapted to maintain said closing means released for free manual manipulation to open and close said valve while the position of said float operated means remains undisturbed.

2. In a feed system for an oil burner, an oil supply tank, a feed line arranged to conduct oil from the tank to the burner, a shut-off device including a shut-off valve interposed in the feed line, an overflow line extending between the burner and said device and arranged to drain excess oil from the burner into said device, valve-closing means carried by said device and oper-

atively connected with said valve, said valve-closing means being adapted to be set and being operable when released to close said valve, means mounted in said device and operable by the rise of the level of oil therein for releasing said valve-closing means, a branch line extending between said feed line and said device, closure-means mounted in said device and normally blocking said branch line, and puncturing-means carried by said valve-closing means and operable thereby when released for rupturing said closure-means to permit drainage through said branch line of oil from the burner and a portion of said feed line into said device.

3. A safety device for oil burners including a casing adapted for connection with a burner bowl to receive excess oil draining from said bowl into the casing, a shut-off valve carried by the casing and adapted to be interposed in a feed line supplying said bowl with oil, spring actuated valve-closing means mounted upon the casing and operatively connected with said valve, said means being adapted to be set and being movable when released to force said valve closed and having a portion disposed to be grasped for manually actuating said means when released to open and close said valve, trigger-means mounted within the casing to coact with said closing means and normally holding said closing means set, and float operated means mounted within the casing to coact with said trigger-means and operable to actuate said trigger-means and release said closing means for movement to close said valve, said closing means when released being movable to close said valve without disturbing the position of said float operated means and said float operated means being adapted to hold said trigger-means in actuated position freeing said closing means for manual manipulation to open and close said valve while the position of said float operated means remains undisturbed.

4. A safety device for oil burners including a casing adapted for connection with a burner bowl to receive excess oil draining from said bowl into the casing, a shut-off valve carried by the casing and adapted to be interposed in a feed line supplying said bowl with oil, spring actuated valve-closing means mounted upon the casing and operatively connected with said valve, said means being adapted to be set, trigger-means mounted within the casing to coact with said closing means and normally holding said closing means set, float operated means mounted within the casing to coact with said trigger-means and operable to actuate said trigger-means and release said closing means for movement to close said valve, means carried by the casing to accommodate a branch line connecting said feed line with the casing, closure-means mounted within the casing and normally blocking said branch line, and puncturing means carried by said valve-closing means and operable thereby when released for rupturing said closure-means to permit drainage through said branch line of oil from the burner bowl and a portion of said feed line into the cas-

5. A safety device for oil burners including a casing adapted for connection with a burner bowl to receive excess oil draining from said bowl into the casing, a shut-off valve carried by the casing and adapted to be interposed in a feed line supplying said bowl with oil, a spring actuated plunger mounted upon the casing and adapted to be set, a trigger pivoted adjacent said plunger and normally holding the plunger set, a lever pivoted

within the casing and operatively connecting said plunger with said valve, said lever being operable by the plunger when released to force the valve closed and said plunger having a portion disposed to be grasped for manually actuating the plunger when released to open and close said valve, and float operated means mounted within the casing to coact with said trigger and operable for actuating the trigger and releasing said plunger, said plunger when released being movable to close said valve without disturbing the position of said float operated means and said float operated means being adapted to hold said trigger actuated and free the plunger for manual manipulation to open and close said valve while the position of said float operated means remains undisturbed.

6. A safety device for oil burners including a casing adapted for connection with a burner bowl to receive excess oil draining from said bowl into the casing, a shut-off valve carried by the casing and adapted to be interposed in a feed line supplying said bowl with oil, a spring actuated plunger mounted upon the casing and adapted to be set, a trigger pivoted adjacent said plunger and normally holding the plunger set, a lever pivoted within the casing and operatively connecting said plunger with the valve, said lever being operable by the plunger when released to close the valve, float operated means mounted within the casing to coact with said trigger and operable for actuating the trigger and releasing said plunger, means carried by the casing to accommodate a branch line connecting said feed line with the casing, a frangible disk mounted within the casing and normally blocking said branch line, and puncturing means carried by said plunger and operable thereby when released for rupturing said disk to permit drainage of oil from the burner bowl and a portion of said feed line through said branch line into the casing.

7. A safety device for oil burners including a casing adapted for connection with a burner bowl to receive excess oil draining from said bowl into the casing, a shut-off valve carried by the casing and adapted to be interposed in a feed line supplying said bowl with oil, a spring actuated plunger mounted upon the casing and adapted to be set, a trigger pivoted adjacent said plunger and normally holding the plunger set, a lever pivoted within the casing and operatively connected at one end with said valve, said lever being provided at its opposite end with a yoke having a slot therein, a pin carried by the plunger and received in said slot for rocking the lever and closing said valve when the plunger is released, said slot accommodating a travel of the plunger greater than the travel of the valve, and float operated means mounted within the casing to coact with said trigger and operable for actuating the trigger and releasing said plunger.

8. A safety device for oil burners including a casing adapted for connection with a burner bowl to receive excess oil draining from said bowl into the casing, a shut-off valve carried by the casing and adapted to be interposed in a feed line supplying said bowl with oil, a spring actuated plunger mounted upon the casing and adapted to be set, a trigger pivoted adjacent said plunger and normally holding said plunger set, means operatively connecting the plunger with said valve and operable by the plunger when released for closing said valve, and a float operated lever pivoted within the casing and provided with a cam-

head to coact with the trigger for actuating the trigger and releasing said plunger.

9. A safety device for oil burners including a casing adapted for connection with a burner to receive excess oil draining from the burner into the casing, a shut-off valve carried by the casing and adapted to be interposed in a feed line supplying the burner with oil, a spring actuated plunger mounted upon the casing and adapted to be set, means normally holding the plunger set, means operatively connecting the plunger with said valve and operable by the plunger when released to force said valve closed, float operated means mounted to coact with said first mentioned means for actuating the same and releasing said plunger, a nipple fixed to the casing and adapted to accommodate a branch line connecting said feed line with the casing, a frangible disk

5 mounted in said nipple and normally blocking said branch line, a removable follower adjustable in said nipple to engage said disk for holding the disk in position, and a prong carried by the inner end of said plunger and operable by the plunger when released for rupturing said disk to permit drainage of oil from the burner into the casing.
